UNITED STATES PATENT OFFICE.

G. W. WALTON AND H. EDGARTON, OF WILMINGTON, DELAWARE.

METHOD OF TURNING ELLIPSOIDAL FORMS.

Specification of Letters Patent No. 15,445, dated July 29, 1856.

To all whom it may concern:

Be it known that we, G. W. WALTON and H. EDGARTON, of Wilmington, in the county of Newcastle and State of Delaware, have 5 invented a new and Improved Machine for Turning Handles for Pails, Tools, &c.; and we do hereby declare that the following is a full, clear, and exact description of the same, reference being had to the annexed drawings, making a part of this specification, in 10 which—

Figure 1 is a longitudinal vertical section of our improvement, (x) (x) Fig. 2 showing the plane of section. Fig. 2 is a plan or 15 top view of the same. Fig. 3 is a transverse vertical section of the same, (y) (y) showing the plane of section.

Similar letters of reference indicate corresponding parts in the several figures. 20 The nature of our invention consists in the employment or use of intermittently rotating feed rollers and expanding cutters fitted within a hollow rotating cylinder, the above parts being arranged and operating 25 as will be hereinafter fully shown and described.

To enable those skilled in the art to fully understand and construct our invention, we will proceed to describe it.

30 A represents a rectangular frame in the upper part of which a hollow shaft B is placed, said shaft working in proper bearings (a) (a) on the frame.

C is a driving pulley on the shaft B and 35 D, is a circular flanch attached to the shaft B, said flanch having a collar E upon it, which collar is attached to two slides F F which work upon the upper part of the frame A. To the shaft B there are attached 40 longitudinally at opposite sides or points two flanches G G, which are grooved and have slides (b) (b) fitted in them. The flanches G are connected with the flanch D and the slides (b) are connected with the 45 collar F. To the slides (b) screws (c) are attached which are fitted in oblique slots (d) in plates H on the flanches G, and to these plates cutters I I¹ are attached. The cutting edges of the cutters of the cutters I 50 passing into the hollow shaft, as shown in Figs. 1 and 3. By shoving the collar E back and forth the cutters I I¹ will be moved in and out from the shaft B, that is from its inner edge or side. This will be understood 55 by referring to Fig. 3. To the back ends of

the slides F F springs J J are connected by rods (e) (e).

In the drawings only one of the cutters I is shown as being allowed to expand, the other I¹ being fixed. This, in some cases, 60 may be preferable, and consequently both or one cutter only may be made to vibrate, as the nature of the work requires.

K K¹ represent two feed rollers placed one over the other and transversely on the 65 frame A directly in front of the shaft B (see Figs. 1 and 2). To the end of the roller K¹ a pinion L is attached.

M is a shaft also placed on the upper part of the frame A and parallel with the rollers 70 K K¹. This shaft has a driving pulley N on one end and a part pinion O on the opposite end.

P P are two rods, one end of which is attached to the slides F F and the opposite 75 ends are hooked or bent and bear upon the shaft M at its end in which pins (f) are placed to act upon the rods P P, as will be presently described.

Q Q are two discharging rollers which 80 are placed on the upper part of the frame A and transversely across the end of the shaft B opposite to the end where the rollers K K¹ are placed.

The operation will be readily seen; motion 85 is given the shaft B by a belt which passes around the pulley C on the shaft B and motion is given the shaft M by a belt which passes around the pulley M; when the teeth of the part pinion O gear into the pinion L 90 95 the feed rollers K K¹ will be rotated and the stick R shown in red will be fed into the hollow shaft B; when the teeth of the part pinion O pass out of gear with the rollers K K¹ the stick of course remains stationary 95 and the pins (f) (f) on the shaft M then draws or acts upon the rods P P and the collar E is moved forward and the cutters I I¹ one or both forced inward by the slides (b) (b) and the cutters act upon the stick 100 R and cut a handle. When the pins (f) (f) pass the hooked ends of the rod P the collar E and cutters I I¹ are brought back to their original position by the springs J J and the teeth of the part pinion O again come in 105 gear with the pinion L and the stick R is again fed a certain distance into the shaft B to be acted upon by the cutters; the handles being cut side by side upon the stick and not quite separated, so that the stick of handles 110

is discharged by the rollers Q Q from the end of shaft B (see Fig. 1).

The above machine is simple in construction, may be cheaply made, is not liable to 5 get out of repair and works rapidly and well.

Having thus described our invention what we claim as new and desire to secure by Letters Patent is—

10 The feed rollers K K¹ and expanding cut-

ters I I¹, one or more attached or fitted to the hollow shaft B when the above parts are arranged and operated as herein shown and described for the purpose specified.

G. W. WALTON.
H. EDGARTON.
